LEAD RULE BROACHER WITH ADJUSTABLY POSITIONED WORK CARRIAGE

Leslie V. York, 132 N. 4th St., and Loren F. Lydium, 115 N. 7th St., both of Fredonia, Kans.

Filed May 2, 1958, Ser. No. 732,742

3 Claims. (Cl. 83—207)

This invention relates to a machine of extremely simple construction for accurately broaching or punching lead rule.

More particularly, it is an aim of the present invention to provide a lightweight, portable machine of extremely simple construction capable of being inexpensively manufactured so as to make it available to small print shops and individual printers, yet which is so constructed that it will provide an extremely accurate machine for correctly punching notches or broaches in an edge of a lead rule.

Another object of the invention is to provide a machine of extremely sturdy construction which may be simultaneously used for punching either single or double notches or broaches in an edge of a lead rule for receiving either a single or a double line, respectively, broaching wire.

A further object of the invention is to provide a machine wherein a carrier supports the lead rule to be broached and is adjustable relative to the punches so that after setting the carrier, and without further adjustment of the machine, a number of lead rules can be provided with either single or double broaches and such broaches or notches will be identically positioned in each rule.

A further object of the invention is to provide a machine wherein no changes or adjustments are required for punching either the single or double type notch or broach.

A further object of the invention is to provide a machine having a scale and pointer, associated with the scale, and which parts are so disposed that the position of each of the punches, relative to the rule, is always clearly visible to the machine operator.

A further object of the invention is to provide a machine having a means for locking the adjustable rule carrier in any adjusted position of the carrier and the lead rule, supported thereby, relative to the two punches so that a number of the lead rules can be uniformly punched without changing the adjustment of the machine.

Various other objects and advantages of the invention will hereinafter become more fully apparent from the following description of the drawings, illustrating a presently preferred embodiment thereof, and wherein:

Figure 1 is a top plan view of the machine;

Figure 2 is a front elevational view thereof, partly in vertical section;

Figure 3 is an enlarged fragmentary rear elevational view of the intermediate portion of the machine;

Figure 4 is an enlarged end elevational view, partly in vertical section, looking from right to left of Figure 2;

Figure 5 is a fragmentary horizontal sectional view, partly in top plan, of the intermediate portion of the machine, and on an enlarged scale, taken substantially along the line 5—5 of Figure 2;

Figure 6 is an enlarged fragmentary vertical sectional view taken substantially along a plane as indicated by the line 6—6 of Figure 2;

2

Figure 7 is a fragmentary horizontal sectional view, taken substantially along a plane as indicated by the line 7—7 of Figure 4;

Figure 8 is an enlarged fragmentary horizontal sectional view, taken substantially along a plane as indicated by the line 8—8 of Figure 2;

Figure 9 is a fragmentary plan view of a portion of a lead rule and showing broaches or notches cut therein, and

Figure 10 is an enlarged fragmentary vertical sectional view taken substantially along a plane as indicated by the line 10—10 of Figure 2.

Referring more specifically to the drawings, the lead rule broaching machine in its entirety is designated generally 12 and includes an elongated frame 13, of substantially arch shaped cross section, as best seen in Figure 4. The frame 13 includes a substantially flat top portion 14, a front wall 15 and a rear wall 16. The walls 15 and 16 extend downwardly from the top wall 14 and are disposed substantially parallel to one another and at right angles to the top wall 14. The walls 15 and 16 have outwardly flanges 17 at their lower ends. The parts 14, 15, 16 and 17 each extends from end-to-end of the frame 13. Foot members 18, preferably formed of rubber, are secured in and depend from the flanges 17 for supporting the frame 13 in a slightly elevated position relative to a supporting surface, such as a table or bench top 19, as seen in Fig. 4. Braces 20 extend between the end portions of the walls 15 and 16 and are secured thereto by nut and bolt fastenings 21 for maintaining said walls parallel to one another.

A carrier or carriage 23 is supported for sliding movement on the frame 13 and includes an elongated top plate 24 which rests upon the top wall 14 and which has a depending flange 25 that extends downwardly from one side edge of the plate 24 and which is disposed against the outer side of the front wall 15 and terminates substantially above the bottom edge of said front wall. The carriage portions 24 and 25 each extends from end-to-end of the carriage 23 and said carriage is of a length greater than the length of the frame 13.

A carriage clamp and guide 26, of a length substantially equal to the length of the frame 13, has a bottom edge portion which is disposed against the lower portion of the outer side of the front wall 15 and which is secured thereto by the brace fastenings 21, which engage said front wall 15, and by additional fastenings 21, which engage the front wall 15 and said bottom portion of the clamp 26, substantially midway of the ends of the clamp, as seen in Figure 2. The clamp 26 includes an upper portion 28 which is outwardly offset relative to the lower portion 27 and which is spaced outwardly from the upper portion of the front wall 15. The portions 27 and 28 of the clamp 26 are joined by an intermediate portion 29 which extends downwardly and inwardly at an incline from the lower edge of the portion 28 to the upper edge of the portion 27. The clamp and guide 26 also includes a substantially flat top portion 30 forming an inturned extension of the upper edge of said upper portion 28 and which overlies a longitudinal portion of the carriage top wall 24, which is located adjacent the front of the frame 13. The depending flange 25 of the carriage 23 fits slidably between the upper portion of the front wall 15 and the upper clamp portion 28, so that the carriage 23 is slidably confined between portions of the top wall 14 and front wall 15 of the frame 13 and the portions 28 and 30 of the guide and clamp 26.

An angular locking lever 31 has a restricted threaded stem 32 projecting from the distal end of the shorter leg 33 of said lever and loosely through aligned openings 34 of the clamp portion 29 and front wall 15, as seen in

Figure 10. A nut 35 is secured immovably to the inner side of the front wall 15, around the opening 34 thereof. The stem 32 extends inwardly through the openings 34 and threadedly through the nut 35. By turning the other handle end 36 of the lever 31 clockwise, as seen in Figure 2, the stem 32 is drawn inwardly through the nut 35 and the distal end of the lever portion 33 is drawn against the outer side of the clamp portion 29, around the opening 34 thereof, so that the clamp portions 28 and 29 are forced toward the front wall 15 for clamping the carriage flange 25 between the portions 15 and 28, to thus lock the carriage 23 immovably to the frame 13.

A bar 37, forming a rule, is disposed on the upper side of the carriage top wall 24 and extends substantially from end-to-end thereof. The rule 37 is disposed between the top portion 30 of the clamp and the rear edge of the carriage top 24 and has one longitudinal edge thereof bearing against the inner or rear edge of the clamp portion 30. The upper surface of the rule 37, along the edge thereof which engages the top portion 30, is suitably marked to form a scale 38 in inches, and the other side edge portion of the top surface of the rule is marked to form pica scale 39. Screw fastenings 40 extend upwardly through the ends of the plate 24 and bar 37, beyond the ends of the scales 38 and 39, and engage in the lower ends of upright handle members 41, for securing the bar or rule 37 immovably on the top plate 24 and for securing the handle members 41 in upright positions above the ends of the rule 37. One end of the bar 37 has a lateral projection forming a transverse shoulder 42 which is disposed in alignment with the zero graduations of the scales 38 and 39 and which faces inwardly of the rule 37, as seen in Figure 1.

A post 43 has an elongated transversely disposed cross-bar or base 44 at the lower end thereof. The crossbar 44 is disposed against the intermediate portion of the rear wall 16, midway of the ends of the frame 13, and is secured thereto by nut and bolt fastenings 45, for mounting the post 43 in an upright position behind the frame 13 and with an inner or front edge of the post 43 disposed behind and spaced from the rear wall 16, as seen in Figures 4 and 6.

A pair of nearly identical punch guides 46 and 47 are disposed against opposite sides of the post 43 and are detachably secured thereto by nut and bolt fastenings 48. The punch guides 46 and 47 have corresponding portions 49 which project forwardly from the inner or front edge of the post 43. Said guide portions 49, as best seen in Figures 4 and 6, have lower ends terminating above and spaced from the top wall 14 and upper ends which terminate substantially below the upper end of the post 43. The guide portions 49 are each provided with a bore 50 of noncircular cross section extending from end-to-end therethrough, as seen in Figure 5. The bores 50 slidably and nonturnably receive shanks 51 of punches 52 and 53, which are supported thereby in upright positions for vertical sliding movement. The punch 52 is supported by the punch guide 46 and the punch 53 is supported by the punch guide 47. Each of the punches has a head 54 at its upper end which is provided with a rounded upper side. A compression spring 55 is carried by the shank 51 of each punch and is disposed under compression between the punch head 54 and the upper end of the guide portion 49 of said punch. The punches 52 and 53 have restricted lower ends, forming extensions of the lower ends of the shanks 51 thereof and constituting the cutting bits of said punches and which are designated 56 and 57, respectively. Said bits 56 and 57 differ in size and shape, as best seen in Figure 8. The bit 56 is substantially triangular in shape in cross section and has one side thereof disposed remote from and facing away from the front edge of the post 43 or in a forward direction. The bit 57 likewise has a forwardly facing wide side, rearwardly converging side walls and a

rearwardly facing narrow side, as clearly illustrated in Figure 8.

Corresponding ends of two levers 58 and 59 are disposed against opposite sides of the upper end of the post 43 and are swingably connected thereto by a nut and bolt fastening 60 which extends through said post and loosely through said lever ends, for mounting the levers for vertical swinging movement up and down above the frame 13. The levers extend forwardly from the post 43 over the punches, and portions of the rounded heads 54 of said punches bear against portions of the bottom edges of the levers 58 and 59. A plate 61 is mounted on and detachably secured to the upper end of the post 43 by a screw fastening 62 and has portions overlying parts of the upper edges of the levers 58 and 59, above the punches 52 and 53, for limiting the extent that said levers can be swung upwardly by the pressure of the springs 55 and for thus limiting the extent that the punches can be moved upwardly to retracted positions by the springs 55. Thus, the springs 55 normally support the punches 52 and 53 and their associated levers 58 and 59, respectively, in the positions as illustrated in Figures 3, 4 and 6, in which positions the punching bits 56 and 57 are disposed above the level of the rule 37. Small plates 63 and 64 are secured to the upper edges of the forward ends of the levers 58 and 59, respectively, to form finger rests or keys. The key 63 has inscribed thereon the letter "S" and the key 64 has inscribed thereon the letter "D," as seen in Figure 1, to designate the single punch 52 and the double punch 53, respectively.

As seen in Figure 5, two tapered pointers 65 and 66 extend from a common base 67. The base 67 is secured to the upper side of the top portion 30 by screw fastenings 68 and the pointers 65 and 66 extend from the base 67 partially across the rule 37. The pointer 65 is disposed in line with the bit 56 of the punch 52 and the pointer 66 is disposed in alignment with the bit 57 of the punch 53.

In using the machine 12, a conventional strip of lead rule 69, of the type used in printing, is placed upon the top wall 24 of the carriage 23 with one longitudinal edge of the lead rule 69 bearing against the rear edge of the rule 37 and with a portion of one end of the lead rule 69 abutting the shoulder 42, as seen in Figure 1. With the lead rule 69 thus disposed, the other longitudinal edge 70 thereof will protrude beyond the rear edge of the top wall 24, as seen in Figures 4 and 6, so that portions thereof will be disposed directly beneath the punch bits 56 and 57. With the clamping lever 31 loosened, as previously described, the carriage 23 can be manually moved longitudinally of the frame 13 by the operator grasping one or both of the handles 41 to accurately set the lead rule 69, carried by said carriage, so that a desired portion of the edge 70 will be disposed directly beneath either the punch bit 56 or 57. The setting of the carriage is accurately indicated visually by the position of the pointers 65 and 66 relative to the pica scale 39, as seen in Figure 5, so that the distance between the right hand end of the lead rule 69 and a portion thereof in which a notch will be cut by either the punch bit 56 or 57, can be accurately determined. When the carriage has thus been properly set, the lever 31 can be turned clockwise, as seen in Figure 2, for clamping the carriage 23 immovably to the frame 13, as previously described, after which any number of lead rules 69 can be punched before resetting the machine 12 and with the assurance that a notch as cut by either the bit 56 or 57 will be in exactly the same position in all of the lead rules. To execute a cut with the punch bit 56, the finger button or key 63 is pressed downwardly to swing the lever 58 downwardly so that the punch 52 is forced downwardly a sufficient distance so that the end of the bit 56 will pass through the lead rule edge 70. A downward force exerted on the other key 64 will cause the same operation to be accomplished by

the bit 57 of the punch 53. As soon as pressure is released on either the button 63 or 64, the depressed punch will be displaced upwardly by the spring 55 to elevate the lever, associated therewith.

The bit 56 will cut a triangular notch 71, as seen in Figure 9, in the lead rule edge 70 and the bit 57 will cut an outwardly tapered notch 72 in the rule edge 70.

The notches 71, formed by the single punch bit 56, are adapted to receive single or light face broaching wire, not shown, and the larger notches 72, formed by the double punch bit 57, accommodate conventional double line or dark face broaching wire, not shown.

Various modifications and changes are contemplated and may be resorted to, without departing from the function or scope of the invention as hereinafter defined by 15

We claim as our invention:

1. In a lead rule broaching machine, an elongated frame of substantially arch shaped cross section including a substantially flat top wall and front and rear walls extending downwardly from and disposed at an angle to the top wall, a clamp connected to and extending upwardly from a lower portion of said front wall and extending substantially from end-to-end of the frame, said clamp being of angular cross section and having a clamping portion spaced outwardly from an upper portion of said front wall and a top portion overlying and spaced upwardly from a part of the top wall, disposed adjacent said front wall, an elongated carriage of angular cross section having a substantially flat top portion resting on said top wall and including a part disposed between the top wall and said top portion of the clamp, said carriage having a depending front portion disposed between said front wall and said clamping portion to retain the carriage against lateral movement relative to the frame, 35 said carriage being supported by the frame for reciprocating movement longitudinally of the frame and clamp,

positioning means fixed to the upper side of the flat top portion of the carriage and adapted to locate a lead rule, supported by the carriage, in a predetermined position relative to the carriage, said positioning means including a portion extending longitudinally of the carriage against which a back edge of the lead rule is adapted to bear and a laterally extending portion against which an end of the lead rule is adapted to abut, said first mentioned portion of the positioning means being disposed between the lead rule and an inner rear edge of said top portion of the clamp, and manually actuated clamping means connected to said front wall of the frame and to the clamp, below said clamping portion, for displacing the clamping portion toward said front wall for releasably clamping the carriage to the frame in a plurality of selected adjusted positions of the carriage longitudinally of the frame to accurately position selected portions of the lead rule beneath a broaching punch supported by the frame.

2. A lead rule broaching machine as in claim 1, and braces extending between and secured to said front and rear walls for maintaining said walls substantially parallel to one another and at right angles to said top wall.

3. A lead rule broaching machine as in claim 2, said front and rear walls having outturned bottom flanges, and foot members secured to and depending from said flanges.
